UNITED STATES PATENT OFFICE.

ARTHUR G. G. GUENTHER, OF CHICAGO, ILLINOIS, ASSIGNOR TO SIGNODE SYSTEM, INC., OF CHICAGO, ILLINOIS, A CORPORATION OF DELAWARE.

SEALING DEVICE.

Application filed February 25, 1918. Serial No. 218,976.

To all whom it may concern:

Be it known that I, ARTHUR G. G. GUENTHER, a citizen of the United States, residing at Chicago, in the county of Cook and State of Illinois, have invented an Improvement in Sealing Devices, of which the following is a specification.

This invention relates to sealing devices for sealing cartons or the like. Shipping cartons in the form of boxes of cardboard and similar material are well known. These cartons frequently have flap covers of various kinds which are folded down on one face of the carton, the carton being subsequently reinforced and secured if necessary as by being bound with metal strap near each end. Pilfering has been a very common incident in the shipping of cartons of this character, it being generally possible for a person to slip his hand through the joint in the flaps in between the reinforcing bands and remove a portion of the contents of the carton without detection.

It is an object of the invention to produce a sealing device for cartons by which the same may be sealed in such a way that pilfering is impossible without detection. In suitable instances, the sealing devices may be used as the only securing means for the carton, the bands being omitted. In the strongest form of package, however, bands or bindings will be supplied, one near each end of the carton, and the sealing means placed in between the bands to seal the flaps of the carton and prevent pilfering.

In the drawings:—

Fig. 1 is a perspective view of one of the co-operating fastener devices made according to my invention;

Fig. 2 is a perspective view of the other device;

Fig. 3 is a perspective view showing these devices as applied to a carton, fragments of the flaps of which are shown in the drawings;

Fig. 4 is a perspective view of a carton having a plurality of sealing devices applied thereon.

In the drawings, 1 represents in general a box or carton having two top flaps 2 and 3 which are folded down, as clearly shown, in Fig. 4, on the top of the carton. My sealing devices are shown in Figs. 1 and 2.

The device of Fig. 1 comprises a metal

fastener, referred to generally as 4, having prongs 5 at one end thereof and an extending tongue 6. The prongs 5 are shown in dotted lines as stamped out of the metal, and in full lines as bent up to be thrust through and bent under the flap of the carton. The co-operating device is shown in Fig. 2 and comprises a sheet metal device 7 having prongs 8 at one end thereof and at the other end a sleeve 9, both formed by bending the portions stamped out of the flat blank and shown in dotted lines in Fig. 2 into the form shown in full lines in the same figure. In applying these devices to a carton, the prongs 5 and 8, after being bent at right angles to the body of the fastener device and forced through the cardboard or other material of the carton, being clenched thereunder as indicated in dotted lines in Fig. 3. These devices are aligned upon the opposite flaps of the carton which it is desired to seal, and when the carton flaps are folded down upon the face of the carton the tongue 6 is slipped through the sleeve 9, which in preferred form is placed with the slot downwardly, after which a crimping tool is applied to the sleeve 9 and tongue 6 enclosed therein, to simultaneously crimp sleeve and tongues together as shown at 11. As many of these seals as desired may be placed across a joint in the carton and will absolutely prevent pilfering without detection.

It will be noted that the devices are extremely simple, the forms shown in Fig. 1 and Fig. 2 above being capable of being stamped from thin sheet metal, and the application of these devices to the cartons is also simple, it being only necessary to force the prongs through the material of the carton and clench them on the under side.

Fig. 4 shows a carton sealed entirely by means of these devices. It is of course to be understood that where shipping conditions require it, reinforcing bands or other binders may be added to the carton, preferably one near either end, so as to properly reinforce the same, in which event the sealing devices shown in Fig. 4 will serve to prevent pilfering and assist in maintaining the carton secure.

Having now described my invention, I claim:—

1. A seal for cartons comprising a metallic fastener secured upon a flap of the car-

ton, a second metallic fastener secured upon another portion of the carton, a tongue on one of the fasteners, a sleeve on the other fastener for the reception of the tongue, 5 said tongue being inserted within said sleeve and the sleeve and tongue being crimped together into locked and sealed relation, the portion of said tongue which is inserted in said sleeve being of uniform width prior to 10 crimping.

2. As an article of manufacture, a fastener element comprising a metal strip having prongs at one end, whereby it may be secured to a carton or the like, and a tongue 15 at the other end, and a sleeve formed on said tongue, adjacent the free end thereof and adapted to be crimped with an enclosed strip into a tension resisting sealed joint.

3. A fibre carton having oppositely disposed flaps, a plurality of tongues secured 20 to each of said flaps extending in opposite directions in overlapping relation and

aligned in pairs, a sleeve formed integral with one of the tongues of each pair and adapted to receive the other tongue of the 25 pair, the sleeve and tongue of each pair being crimped together to provide a sealed tension resisting joint connecting said tongues.

4. A fibre carton having oppositely disposed flaps, a tongue secured to each of said flaps, said tongues extending in opposite directions in aligned, overlapping relation, a sleeve formed integral with one of said tongues and adapted to receive the other 35 said tongue, said sleeve and tongue being longitudinally crimped to provide a taut band connecting said flaps with the edges of the crimped portions disposed upon the inner side of said band.

40 In testimony whereof, I have signed my name to this specification.

ARTHUR G. G. GUENTHER.
